UNITED STATES PATENT OFFICE.

HENRI LECOQ, OF LE HAVRE, FRANCE, ASSIGNOR TO CHANTIERS & ATELIERS
AUGUSTIN NORMAND, OF LE HAVRE, FRANCE, A CORPORATION OF FRANCE.

GUN TURRET FOR SUBMARINES.

Application filed December 22, 1921. Serial No. 524,252.

To all whom it may concern:

Be it known that I, HENRI Lecoq, citizen of the French Republic, residing at Le Havre, Department of the Seine Inférieure, in France, have invented certain new and useful Improvements in Gun Turrets for Submarines; and I do hereby declare the following to be a full, clear, and exact description of the invention, such as will enable others skilled in the art to which it appertains to make and use the same.

The present invention has for its object to place the gun or guns of a submarine in a turret intended for the protection of the gunners, this turret being moreover incorporated in the body of the super-structure itself in such a manner as to lengthen the contour thereof and thus reduce the resistance to movement of the submarine when submerged.

The accompanying Figures 1 to 6 show two methods of carrying out the invention. Figures 1, 2 and 3 applying to one example whilst the Figures 4, 5 and 6 refer to another example. In each case the figures show a section of that part of the submarine in which the turret is located, a plan and an end view of the turret in elevation.

In the example selected, both in the Figures 1 to 3, and 4 to 6 it is assumed that the turret is located in front of the superstructure body; the construction would be the same in the case where the gun or guns were placed at the back of the said body.

The reference numerals are the same in the two series of Figures 1, 2, 3 and 4, 5, 6.

The crew enters the turret 1 through the upper part of the dome which is provided with a wide opening 2 without a closing device. The turret encloses, in addition to the gun and its crew, a magazine for ammunition in which the shells 4 are simply stored in the ordinary manner, but in which the charges are enclosed in separate water tight casing capable of offering resistance at the maximum submersion depth of the submarine.

On the side opposite to the breech of the gun in its position of rest there is a second ammunition magazine also having charges in separate casings, and holding shells. This magazine is likewise provided with an aperture without a closing device in the upper part of its dome. This aperture permits the turret to be supplied with ammunition. The plates of the vault and the turret are pierced with openings which permit the free access of the sea water to these two parts at the moment of submersion.

In the arrangement shown in Figures 1, 2 and 3 provision is made for the crew to pass along the turret at 3 (without entering it), by means of foot bridges or gangways arranged on each side of this turret 65 at the height of the deck. The walls of the lower part of the turret lengthen the contour of the lateral side of this deck.

In the second arrangement shown in Figures 4, 5 and 6, provision is made for 70 widening the deck of the submarine in such a way that the lower part of the turret can turn completely; in this case the lower part of the turret is simply provided with the gang-ways 3 insuring the continuity of the 75 deck in the position of rest.

Claims:

1. In a submarine, the combination with the superstructure thereof, of a turret, the fore and aft exterior lines thereof being 80 continuations of analogous lines of the super-structure, said turret being placed at the end of the super-structure.

2. In a submarine, the combination with a stream line superstructure, of a turret, the 85 fore and aft exterior lines of said turret when the same is in normal position, being continuations of analogous lines of the superstructure, said turret being placed at the end of the superstructure, whereby 90 resistance is reduced to a minimum during submersion.

In testimony whereof I affix my signature.

HENRI LECOQ.
